CLAIM

The ornamental design for the aircraft seating configuration, as shown and described.

DESCRIPTION

FIG. 1 is a front left elevated isometric view of the aircraft seating configuration;

FIG. 2 is a top plan view of the aircraft seating configuration;

FIG. 3 is a right side plan view of the aircraft seating configuration; and,

FIG. 4 is a left side plan view of the aircraft seating configuration.

The broken lines shown in the drawings illustrate portions of the article that form no part of the claimed design.

1 Claim, 4 Drawing Sheets
